UNITED STATES PATENT OFFICE.

SAMUEL P. MARTIN, OF DE GRAFF, MINNESOTA.

SWEET-RAKE.

No. 927,740.

Specification of Letters Patent.

Patented July 13, 1909.

Application filed May 23, 1908. Serial No. 434,630.

To all whom it may concern:

Be it known that I, SAMUEL P. MARTIN, a citizen of the United States, residing at De Graff, in the county of Swift and State of Minnesota, have invented certain new and useful Improvements in Sweep - Rakes, of which the following is a specification, reference being had to the accompanying drawings.

My invention relates to improvements in sweep rakes, and its object is to improve and simplify the construction of devices of this character and thereby render the same less expensive and more durable and efficient.

With the above and other objects in view the invention consists of the novel features of construction and the combination and arrangement of parts hereinafter fully described and claimed, and illustrated in the accompanying drawings, in which—

20 Figure 1 is a plan view, with parts broken away, of my improved sweep rake; Fig. 2 is a side elevation; Figs. 3, 4 and 5 are detail sectional views taken on the planes indicated by the lines 3—3, 4—4 and 5—5 in Fig. 1; Fig. 6 is a detail view of the seat support; and Fig. 25 7 is a detail perspective of the rear end of one of the end members of the body frame.

My improved rake comprises a body frame consisting of two similar end blocks 1 which 30 taper from front to rear and are connected at their front by upper and lower longitudinal bars 2, 3 and at their rear by a longitudinal bar 4. The lower front and rear bars 3, 4 are connected at intervals by cross bars 5, said 35 bars 2, 3, 4, 5 having their ends mortised into each other and the end blocks or heads 1 and secured by bolts or similar fastenings 6.

7 denotes the teeth of the rake. These teeth are arranged parallel to each other and 40 beneath the cross bars 5 and the front and rear bars 3, 4 to which they are detachably connected. This connection is effected by forming in the bottom edge of the lower or bottom bars 3, 4 of the frame transverse 45 grooves or seats 8 to receive the rear portions of the teeth, the extreme rear ends of the latter being recessed or mortised, as at 9, to engage the recesses 8 in the rear bar 4 and to provide shoulders 10 which will prevent 50 the teeth from shifting rearwardly. The teeth are secured in the recesses 8 of the bottom bars by U-shaped bolts or clips 11 which are passed over and arranged in seats 12 in the tops of the cross bars 5 and have 55 their depending ends formed with eyes 13

disposed on opposite sides of the teeth and adapted to register with transverse openings in the latter so as to receive removable bolts 14. It will be seen that by constructing the frame and the teeth as illustrated and attaching the latter as just described, said teeth may be readily disconnected from the frame to permit it to be stored away when not needed and that should the teeth break they may be readily replaced by new ones. 60

15 denotes castor wheels, two of which are preferably provided for supporting the frame. The hangers 16 of the wheels are swiveled to the lower ends of standards 17 which are adjustable both vertically and horizontally in 70 supporting blocks or members 18. The blocks 18 extend crosswise of the frame 1 and have at their ends projecting portions or arms 19 which are bolted as at 20 to the bars 2, 3, 4. In the blocks 18 are formed longitudinal series of vertical openings 21 in any of which the standards 7 may be inserted and adjusted vertically, preferably, by inserting removable pins or bolts 22 through transverse openings 23 in the blocks 18 and 75 openings 24 arranged in said standards. A plurality of the openings 24 are arranged in each standard 17 so that any one of them may be brought into register with the openings 23 in the block 18 to receive the adjusting pin 22.

Detachably pivoted by a bolt 25 upon the outer side of each of the end blocks or heads 1 is a draft tongue or pole 26 and projecting outwardly from each side or end of the frame 90 is an evener or draft bar 27. The latter has adjustably mounted upon its outer end a whiffletree 28 and its inner end is detachably connected to the frame by two bolts 29, 30 the former of which is passed through the 95 rear bar 4 and the latter of which passes through two rearwardly projecting lugs 32 projecting from one of the end blocks or heads 1 and adapted to receive the evener bar 27 between them.

33 denotes a driver's seat adjustably secured upon a seat standard 34 which is loosely connected to the frame by a bolt 35 and is resiliently supported in an inclined position by a curved spring 36. The ends 105 of the latter are secured at 37 to the frame and its central portion supports the standard 34 and is provided with foot rests 38.

39 denotes a bar for spacing the outer portions of the teeth 7 apart and reinforcing 110

them. This bar is preferably removably arranged upon the teeth by forming in its top recesses 40 to receive said teeth and by providing upon it above said recesses U-shaped straps 41 which project over the teeth. To retain the spacing and supporting bar 29 upon the teeth I preferably provide in certain of the straps 41 removable pins 42 which enter openings or sockets in certain of the teeth. Said pins 42 may be connected by straps or chains 43 to the bar 39 to prevent them from being lost.

Having thus described my invention what I claim is:

15. 1. In a device of the character described, the combination of a body frame having end members connected by longitudinal bars and cross bars connecting said longitudinal bars, teeth engaged with said longitudinal bars and having shoulders to prevent them shifting rearwardly, clips passed over the cross bars and engaged with the teeth and transverse fastenings passed through the clips and the teeth.
20. 2. In a device of the character described, the combination of a body, rake teeth projecting forwardly therefrom, a spacing and strengthening bar having its upper edge recessed to receive the teeth, straps extending over the recesses of said bar to receive the teeth and pins passed through the straps and into the teeth to secure said bar thereto.
25. 3. In a device of the character described, the combination of a body, rake teeth projecting forwardly therefrom, a spacing and strengthening bar extending across and engaged with the forward ends of said teeth

and means for detachably securing said bar to said teeth.

4. In a device of the character described, the combination of a body having end members provided at their rear ends with spaced lugs, longitudinal bars connecting said end members, teeth carried by said longitudinal bars, draft tongues or poles projecting forwardly from the end members, and draft bars or eveners projecting outwardly from the body and having their inner ends secured to the longitudinal bars and their intermediate portions secured between the spaced lugs on the end members.

5. In a device of the character described, the combination of a body frame having upright end members connected by longitudinal bars and cross bars connecting said longitudinal bars, rake teeth engaged with the longitudinal bars and having shoulders to prevent them from shifting rearwardly, clips detachably connecting the teeth to said cross bars, a draft tongue detachably connected to each of the end members and projecting forwardly therefrom, a draft bar or evener detachably connected to the end members and longitudinal bar of the body and projecting outwardly therefrom, and detachable caster wheels adjustable both vertically and forwardly and rearwardly from the body, substantially as described.

In testimony whereof I hereunto affix my signature in the presence of two witnesses.

SAMUEL P. MARTIN.
